Specification of Letters Patent. Patented Feb. 6, 1917.

Application filed March 6, 1915. Serial No. 12,592.

To all whom it may concern:

Be it known that I, JOHN HERZOG, a citizen of the United States, residing at Saginaw, in the county of Saginaw and State of Michigan, have invented certain new and useful Improvements in Cabinets; and I do hereby declare the following to be a full, clear, and exact description of the invention, such as will enable others skilled in the art to which it appertains to make and use the same.

This invention is a cabinet, and pertains more particularly to that class of cabinets commonly employed for holding music, papers and the like.

The object of my invention is to provide a cabinet of neat and attractive appearance and of strong and durable construction, having no door, but being capable of being opened to expose the contents of the cabinet, or closed to conceal the contents, the exterior dimensions of the cabinet being the same, and its shape being the same whether the cabinet is open or closed.

A further object is to provide a revolving shelf- or drawer-holding case within the cabinet and a pivotal supporting means for the case, the pivotal supporting device serving not only to support the case, but also to retain the proper alinement of the revolving case and the stationary top and bottom of the frame of the cabinet, this result being accomplished in my construction without employing any through-bolt or other rod extending through the body of the case.

With these and certain other objects in view which will appear later in the specification, my improvement consists in the devices described and claimed and the equivalents thereof.

In the drawings, Figure 1 is a front elevation of the cabinet closed. Fig. 2 is a front elevation with the cabinet open, showing the shelves of the revolving case. Fig. 3 is an enlarged horizontal section on the line 3—3 of Fig. 1. Fig. 4 is an enlarged transverse section through the lower bearing taken on the line 4—4 of Fig. 3.

As is clearly shown in the drawings, the cabinet consists of a frame comprising a base 1 provided with suitable legs, a body or frame 2 fixed to the base and forming a part of the front, one side, the back, and part of the other side, as shown in Fig. 3. The top 3 is fixed to the body 2 and projects over the base 1. Between the base 1 and the top 3

is a revoluble three-sided case 4, one side and the back of which form the remaining parts of the front and side of the cabinet when closed, as shown in Fig. 3. The front 60 of the case 4 may be provided with a suitable knob or handle 5.

6 represents the bottom of the case and 7 the top. Suitably mounted on the sides of the case are a number of shelves 8, or their 65 equivalents. The bottom 6 of the case is pivotally mounted on the base 1 of the frame by a ball bearing pivot, the construction of which will be presently described. The top 7 of the case and the top 3 of the frame are 70 connected by a bearing similar to and in alinement with the lower bearing.

When the cabinet is closed it is preferably rectangular in cross section, as shown in Fig. 3, the front and side members of the body 2 75 and the side and back members of the revolving case 4 being in alinement and presenting the appearance of a continuous front and back.

When the case 4 is revolved by taking 80 hold of the knob or handle 5, it turns in the direction indicated by the arrows in Fig. 3, past the position indicated by dotted lines, until the open front of the case comes into line with the front of the frame, as shown 85 in Fig. 2, thus exposing the shelves and their contents. When in this position the contour of the cabinet is the same as when the cabinet is closed and it occupies the same amount of space, which would not be possible if the 90 cabinet were fitted with swinging doors. It will be noted that there is no central rod extending up through the revolving case. It is necessary, however, to securely tie together the top 7 of the case and the top 3 of 95 the frame to prevent their warping or getting out of line and thereby showing unsightly cracks at the upper and lower extremities of the revolving case adjacent the top 3 and the base 1.

To provide an easy turning pivot of simple and inexpensive construction that is capable of preserving the alinement of the frame members, I have produced the bearing shown in cross section in Fig. 4, in which 9 105 is a bottom plate secured to the base 1 and formed with a circular ball race 10. 11 is a similar but smaller top plate formed with a ball race 12 and secured to the bottom plate 9 by the clamping bolt 13 and nut 14. 110

Received between the plates 9 and 11 is an intermediate plate 15 having an offset

flange secured to the bottom 6 of the case 4. The intermediate plate 15 is formed with two ball races, one of which, 16, is formed on the underside of the plate and registers with ball race 10 of plate 9, and the second ball race of intermediate plate 15 is formed on the upper side of the plate and registers with the ball race 12 of the top plate 11. Suitable steel balls are provided, as in ordinary ball bearings.

The downward thrust and weight of the revolving case and its contents is sustained by the lower ball race, and any tendency for the base 1 and the top 3 of the cabinet frame 15 to warp apart or otherwise separate is resisted by the ball bearing on the upper face of the plate 15, as will be clearly understood from inspection of Fig. 4. By means of this bearing the rigidity of the entire cabinet is maintained, enabling the revolving case to turn noiselessly and with the greatest ease. This smoothness can not be affected by any ordinary degree of warping of either the frame or the revolving case.

25 It will be seen from Fig. 3 that the depth of the stationary body 2 is just sufficient to permit the corners of the revolving case to turn, as indicated by the arrows, when the cabinet is being opened or closed.

30 By the means above described, I have produced a simple and comparatively inex-

pensive cabinet of neat and compact design, that is capable of carrying heavy loads and of being opened and closed without sticking or binding.

Having thus described my invention, what I describe and desire to secure by Letters Patent is:

In a cabinet, a stationary frame having a base and top, and a case revolvably mounted 40 therein, pivotal connections between the top of said case and the top of the body and between the bottom of the case and the bottom of the frame, said connections adapted to prevent separation of the top and bottom 45 members of the body and case respectively, each of said connections comprising a bottom plate secured to the frame of the cabinet, said bottom plate formed with a ball race, a top plate formed with a ball race, said top 50 and bottom plates secured together in spaced relation, an intermediate plate secured to said revolvable case, said intermediate plate formed with a ball race on each side thereof and registering respectively with the ball 55 races of said top and bottom plates.

In testimony whereof, I affix my signature in presence of two witnesses.

JOHN HERZOG.
